UNITED STATES PATENT OFFICE.

ROBERT EMMET KEOUGH, OF MONTREAL, QUEBEC, CANADA, ASSIGNOR TO THE AMERICAN FORK & HOE COMPANY, OF CLEVELAND, OHIO, A CORPORATION OF OHIO.

RAIL-JOINT SHIM.

Application filed November 11, 1927, Serial No. 232,539. Renewed January 31, 1929.

This invention relates to an improvement in rail joint construction and more particularly relates to wear compensating means for rail joints whereby rail joint bars which have 5 become worn by the movement of the rail ends in the joints and which bars are sufficiently strong to meet the requirements of use, may be continued in use in connection with either worn rails or new rails.

10 In the practical use of a rail joint, the hammering down of the rail ends by the passage of the trucks of trains passing over the rails, results in wear at the undersides of the bottom corners of the rail heads at 15 their ends, and principally rail joint side bars below the rail heads.

In my pending application Serial No. 99,475, filed April 3, 1926, I disclosed wear compensating means adapted to be inserted 20 in the crevice thus formed comprising "whole" and "half" type shims of gradually increased thickness proceeding toward the ends of the rails, that is toward the middle of the joint in order to compensate for the 25 progressively increased wear occurring towards the ends of the rails. The present invention pertains to shims of the "half" type.

An object of my invention is to provide a 30 wear compensating shim for rail joints which will not be subject to displacement longitudinally of the joint.

Another object of my invention is to provide an improved wear compensating means 35 for rail joints which are adapted to fill the crevice resulting from wear in such a way that the crevice will be substantially filled in all portions.

Other objects of my invention and the invention itself will become apparent by reference to the following description of certain 40 embodiments of my invention and in which description reference will be had to the accompanying drawings forming a part of this specification.

45 In the drawings:

Fig. 1 is a perspective view illustrating an application of the invention indicating the position assumed by the shim in the rail joint, partially by dotted lines.

50 Fig. 2 illustrates in side elevation a joint as illustrated in Fig. 1 with the joint bars removed but with the shims at one side of the rails shown in place.

55 Fig. 3 illustrates in perspective a pair of shims of the "half" type indicated also in

the foregoing figures and forming an embodiment of my invention.

Referring now to all the figures of drawings in all of which like parts are designated by like reference characters, bearing members or shims are made preferably of steel capable of standing the pressure and wear of service and each of the shims is adapted to be placed or inserted between the head 60 of the bar B and the end side of the rail head at and contiguous to the end of the rails R so that the pair of shims will occupy the central or medial part 65 of the rail joint. Each shim is preferably of angle formation having an upper flange part 2 which lies between the worn head of the bar and the opposing end side surface of the rail head, and an apron part 1 having a depending extension 3 at the 70 thicker ends of the shims. Each of the bearing members or shims is tapered in thickness from their ends 4 toward their ends 5, the thicker ends 4 being adapted to be disposed adjacent the ends of the rails R and 75 the thinner ends 5 adapted to be disposed most remote from the ends of the rails. The apron extensions 3 preferably extend downward from the thickened ends of the shims 80 and are adapted by their lateral edges 6 to 85 engage the bolts 7 securing the joint bars B to the rails in their portions most nearly adjacent the ends of the rails.

By reason of the employment of a pair 90 of bearing members or shims the upstanding burr or fin of metal at the head of the bar, designated by the reference numeral X is avoided and does not have to be trimmed, ground, or hammered down to permit of the re-use of the bar on an old or new rail 95 with shims of the kind described. In that way considerable economy is effected in the installation of the present shims, and furthermore the arrangement permits of the use 100 of shims, of different thickness if desired at each side of the meeting ends of the rails to meet a case of unequal wear. For example, if it is found that wear under one rail head is greater than the other due to 105 heavier traffic in one direction, a shim of greater thickness at its end nearest the joint may be used in combination with a thinner shim at the other side. The arrangement set forth permits of a wide range of practical combinations for repairing the worn bar 110 head and underside of the rails with a minimum of labor and expense.

It will be seen that the shims, in angular form, are disposed within the rail joint with the apron 1 extending between the rail webs and the joint bars and that the apron extensions 3 occupy such a position in the joint as to prevent lateral movement of the "half" type shims longitudinally in the joint in a direction away from the ends of the rails. This prevents displacement of the shims in use and insures always that the thickest part of the shim will occupy the widest portion of the crevice occasioned by wear of the rail joint and conversely insures that the thicker part of the shim will not travel to narrower portions of the crevice resulting in an improperly supported or floating rail end.

The present application is divisional in part from applicant's previously filed application, Serial No. 99,475, filed April 3, 1926.

Having thus described my invention in a particular embodiment, I am aware that numerous and extensive departures may be made from the embodiment herein illustrated and described and without departing from the spirit of my invention.

I claim:

1. A wear compensating means for rail joints comprising a pair of separate metallic shim members, each progressively thickened in the direction of its length toward the center of the joint, said bars being each of uniform thickness on each line of cross-section extending transversely of the joint.

2. A wear compensating means for rail joints comprising a pair of separate metallic shim members, each tapering in thickness toward one end, and the thickened ends adapted to be placed adjacent each other between the underside of a rail head and the upper edge of a joint bar, said bars being each of uniform thickness on each line of cross-section extending transversely of the joint.

3. A wear compensating means for rail joints comprising a pair of separate metallic shim members, each member consisting of an angular section tapering in thickness toward one end and adapted to be positioned between the underside of the head of a rail end and the upper side of a joint bar.

4. A wear compensating means for rail joints consisting of separate metallic shim members of angular cross section and each tapering in thickness toward one end, and the thickened ends of said members being adapted to be disposed toward each other and spaced apart beneath the ends of adjacent rail heads and above the upper edge of the joint bar.

5. A wear compensating means for rail joints consisting of separate renewable and interchangeable metallic shim members of angular cross section, each of said members consisting of a body tapering in thickness toward one end.

6. A shim for worn rail joints comprising

ing a body of angular cross section progressively thickened from one end toward the other, providing an enlarged end adapted to fill the worn portions between the underside of the rail head and the joint bar.

7. A wear compensating means for rail joints comprising a pair of separate metallic shim members, each member consisting of an angular section tapering in thickness toward one end and adapted to be positioned between the underside of the head of a rail end and the upper side of a joint bar, said shim comprising a depending apron extension of lesser width than the bearing portion of the shim adapted to be disposed between the inner bolts of a rail joint for engagement therewith to prevent longitudinal shifting of the shim in the joint.

8. A wear compensating means for rail joints consisting of separate metallic shim members of angular cross section and each tapering in thickness toward one end, and the thickened ends of said members being adapted to be disposed toward each other and spaced apart beneath the ends of adjacent rail heads and above the upper edge of the joint bar, said shim comprising a depending apron extension of lesser width than the bearing portion of the shim adapted to be disposed between the inner bolts of a rail joint for engagement therewith to prevent longitudinal shifting of the shim in the joint.

9. A wear compensating means for rail joints consisting of separate renewable and interchangeable metallic shim members of angular cross section, each of said members consisting of a body tapering in thickness toward one end, said shim comprising a depending apron extension of lesser width than the bearing portion of the shim adapted to be disposed between the inner bolts of a rail joint for engagement therewith to prevent longitudinal shifting of the shim in the joint.

10. A shim for worn rail joints comprising a body of angular cross section progressively thickened from one end toward the other, providing an enlarged end adapted to fill the worn portions between the underside of the rail head and the joint bar, said shim comprising a depending apron extension of lesser width than the bearing portion of the shim adapted to be disposed between the inner bolts of a rail joint for engagement therewith to prevent longitudinal shifting of the shim in the joint.

11. A shim for rail joints adapted to be placed between a rail joint side bar and one of a pair of substantially abutting rails, of metallic material of substantially continuously decreasing thickness toward one of its ends, said shim being of substantially uniform thickness on each line of cross-section extending transversely thereof.

12. A shim for worn rail joints comprising

70

75

80

85

90

95

100

105

110

115

120

ing a body of angular cross section progressively thickened from one end toward the other, providing an enlarged end adapted to fill the worn portions between the underside 5 of the rail head and the joint bar, and a depending portion engageable with a transversely extending part of the rail joint to prevent longitudinal displacement of the shim in the joint.

10 13. A wear compensating means for rail joints consisting of separate renewable and interchangeable metallic shim members of angular cross section, each of said members consisting of a body tapering in thickness

toward one end, and comprising a depending extension at its end of greatest thickness.

14. A wear compensating means for rail joints comprising a pair of separate metallic shim members, each progressively thickened in the direction of its length toward the center of the joint, and each engageable with a transversely extending element of the joint to prevent its longitudinal displacement in the joint.

In testimony whereof I hereunto affix my 25 signature this 1 day of November, 1927.

ROBERT EMMET KEOUGH.
